UNITED STATES PATENT OFFICE.

WILLIAM W. DONALDSON, OF KEWANEE, ILLINOIS.

COMBINED ADVERTISING MEDIUM AND FLY-TRAP.

1,024,187.

Specification of Letters Patent.

Patented Apr. 23, 1912.

Application filed October 21, 1911. Serial No. 656,076.

To all whom it may concern:

Be it known that I, WILLIAM W. DONALDSON, a citizen of the United States, residing at Kewanee, in the county of Henry and State of Illinois, have invented a new and useful Combined Advertising Medium and Fly-Trap, of which the following is a specification.

This invention relates to certain improvements in combined advertising mediums and fly traps.

The invention has for its object to provide for and to promote commercial advertising and, in connection therewith, to effect the entrapping of flies.

A further object is to effect these purposes in an extremely simple, economical and ready manner.

A still further object is to carry out these ends with sanitary conditions in view, by providing for destroying or incinerating both the entrapping medium and the entrapped dead flies finally.

The invention consists of certain instrumentalities and features substantially as hereinafter fully disclosed and defined by the claims.

In the accompanying drawing, illustrating the preferred embodiment of my invention wherein it will be understood that various changes and modifications may be made as relates to the detailed construction and arrangement of the parts without departing from the spirit thereof, Figure 1 is a perspective of the device. Fig. 2 is a front elevation, partly in section, thereof. Fig. 3 is a view of the same viewing upwardly from within. Fig. 4 is a view of the device folded.

40 In practising my invention, I construct or form the same preferably from some inexpensive and suitable material, as paper and the like, the rates of manufacture of which will allow of the gratuitous distribution thereof in a commercial way in adapting the same for advertising purposes, as will be more fully appreciated from the following.

The device or contrivance designated generally as 1, is constructed or formed preferably in substantially pyramidal outline, the details of such construction being carried out in any suitable way which it is thought is not necessary to describe herein.

55 Each of two sides or lateral walls 2 of the device is preferably of imperforate paste-

board, or like material, of sufficient stiffness or stability to enable the same to stand in upright position, and which are joined so as to be collapsible or foldable as disclosed by Fig. 4. The remaining or front-side or wall 3 of the device is preferably of netting or textile material to allow of the ready co-operation thereof with the lateral walls in rendering the device collapsible or foldable, and which aids in admitting light therein, especially as desirable in connection with the chamber of a fly trap.

Interiorly of, and suitably attached at its lower edges to the walls of the device, as thus far constructed, is a bottom-member 4 preferably of oiled paper, netting or like material, and also of pyramidal outline, with its tapering portion or point of convergence terminating in a tubular member 5 for the upward passage of the flies there-through, into the entrapping chamber 6, as the resultant of the pyramidal structure.

The device or structure is adapted to be supported upon leg-forming downward-extensions 7 of the stiff or paste-board walls thereof, to provide passages 8 for directing the flies finally into the trap, as presently seen.

The device or structure is adapted to have advertising matter displayed more particularly upon its stiff or paste-board walls, as is apparent, and thus serve as a combined fly-trap and advertising medium, the same being as previously stated, distributed commercially, while it may be also placed in dwellings or elsewhere for use.

Preliminary to disposing or setting the trap or device, a piece of paper, with a quantity of molasses thereon, is suitably placed to attract the flies; when this has been effected, the trap or device is placed over the molasses-treated paper: the attracted flies, in attempting to escape and in their naturally upward-flight, will be directed by the upwardly converging portions of the bottom-member 4 into and through the tubular member 5, which will result in entrapping the flies in the chamber 6, as is apparent.

What is claimed is:—

1. A device of the character described, including lateral and front foldable walls, together with a converging foldable bottom-member having a passage-forming tubular member at its point of convergence.

2. A device of the character described,

combining an advertising medium and a fly-trap including lateral and front foldable walls, together with a converging foldable bottom-member, having a passage-forming tubular member at its point of convergence, said lateral walls having leg-forming downward extensions.

3. A device of the character described, combining an advertising medium and a fly-trap, including lateral and front foldable walls, together with a foldable converging bottom-member, said lateral and front walls being arranged in pyramidal outline and said bottom-member having a passage-forming tubular member at its point of convergence.

4. A device of the character described, combining an advertising medium and a fly-trap, including lateral and front foldable walls, together with a foldable bottom member, said lateral and front walls being arranged in pyramidal outline, said bottom-member also being of like outline, the tapering or converging upper portion of said

bottom-member having applied thereto a passage-forming tubular member.

5. A device of the type described, including upwardly converging foldably connected walls, and an upwardly converging bottom foldably connected to said walls, at their lower edges, said bottom having a passage-forming tubular member at its point of convergence.

6. A device of the type described, including upwardly converging foldably connected walls, and an upwardly converging bottom foldably connected to said walls at their lower edges, said bottom having a passage-forming tubular member at its point of convergence, one of said walls and the forming members of said bottom being foraminous.

In testimony that I claim the foregoing as my own, I have hereto affixed my signature in the presence of two witnesses.

WILLIAM W. DONALDSON.
